UNITED STATES PATENT OFFICE.

JOHN PFEIFER, OF SPRINGFIELD, OHIO, ASSIGNOR TO MAST, FOOS & COMPANY, OF SAME PLACE.

CASH-REGISTER.

SPECIFICATION forming part of Letters Patent No. 673,784, dated May 7, 1901.

Application filed June 24, 1899. Serial No. 721,724. (No model.)

To all whom it may concern:

Be it known that I, JOHN PFEIFER, a citizen of the United States, residing at Springfield, in the county of Clark and State of Ohio, have 5 invented certain new and useful Improvements in Cash Registers and Indicators, of which the following is a specification.

My invention relates to cash registers and indicators, and has for its objects improvements in the constructions of machines of this 10 class, and especially such as set forth in my Patents No. 579,694, dated March 30, 1897, and No. 642,713, dated February 6, 1900. It especially relates to improvements in the transferring devices for such machines.

In the accompanying drawings, Figure 1 is a partial sectional elevation of my invention. Fig. 2 is a top plan view with parts broken away. Fig. 3 is a transverse sectional view 20 of parts of the transferring devices. Fig. 4 is a sectional view more in detail of parts of the transferring devices. Fig. 5 is a top plan view of the keys and the transferring devices for the keys. Fig. 6 is a detail view of my 25 key-transferring device. Fig. 7 is a detail view of parts of the transferring device. Fig. 8 is a perspective view of my machine with some of the parts omitted. Fig. 9 is a detail view of the sliding bar and connecting parts. 30 Figs. 10 and 11 are detail views of parts of my device.

Like parts are represented by similar characters of reference in the several views.

The general features of construction are 35 preferably those described and shown in my prior patents referred to, and in this application I have shown cash-keys a , numbered corresponding to the amounts to be registered and indicated. These keys are arranged in 40 connection with the indicating and registering devices, the same as in my former patents. The cash-keys a are normally locked and can only be operated after the lever b has been moved from its normal position, the movement 45 of said lever and the rotating shaft l connected thereto, being adapted to unlock the cash-keys and accomplish the movement required to operate the indicating and registering devices after the key has been moved. The 50 graduated bars a^3 are adapted to accomplish the proper movement of the indicating and

registering devices, said graduated bars a^3 being hung on the main shaft l and having backwardly-extending arms a^6 , which are pivotally connected to the vertically-moving racks by 55 means of suitable links. The rack a^4 engages a pinion on the indicating-disks to move the same when said rack is moved. Arranged adjacent to each of said racks there is a counter, which may be of any well-known construction, consisting of a series of counting-wheels, each numbered from "0" to "9" and geared together, so that a complete rotation of one produces a movement of one unit of the other. These counters are adapted under certain 65 conditions to be connected to the racks and move therewith by the following devices: There is pivoted to a suitable part of the frame and adjacent to each of the racks a lever b^2 , which carries at its outer end a pinion b^3 , 70 which is normally out of engagement with the rack, but is adapted by a movement of the lever b^2 to be thrown into mesh therewith. A pinion b^4 on the lever b^2 meshes with the lever-pinion b^3 , and said pinion b^4 has a long 75 sleeve b^5 , which carries at its outer end a toothed number-wheel.

My devices for transferring from one counter to the counter of next higher denomination are as follows: Adjacent to the pinion b^4 I 80 pivot a lever b^7 , which is formed with a stud b^8 on one side, said stud being beveled at the top and adapted to stand in the path of a projection b^9 on the sleeve of the pinion b^4 . At the lower end of said lever b^7 I attach an 85 arm b^{10} , which is pivoted to a stop-lever b^{11} , pivoted to the upper part of the frame. Said lever b^7 has a spring b^{14} attached at the upper end, connecting same with the lower projecting arm of a latch b^{12} , having an arm b^{13} 90 extending upwardly. The end of said latch is adapted to drop over a projection b^{15} near the center of the lever b^{11} , where the arm b^{10} is pivoted to said lever when said lever has been moved from normal position. The lower 95 end of the lever b^{11} in its normal position stands opposite a stop d^6 , pivoted on an upwardly-projecting arm d , pivoted on the shaft 4. A spring extends from said arm d to a plate d' , as shown in Fig. 1. Said plate is 100 fastened to the upwardly-projecting arm a^7 of the graduated arm a^3 and has a slot d^2 in

its rear end. A pin d^3 , extending from the arm d , fits into said slot d^2 of the plate d' , which by means of said spring permits said limited movement of the arm d independent 5 of the graduated bar a^8 and tends to keep said arm d in contact with the roller d^{11} , as shown in Fig. 1. At the upward end of said arm d , opposite the pivoted stop d^5 , there is pivoted a corresponding stop d^6 , which is held 10 normally in close contact with the stop d^5 by a spring, as shown in Fig. 1. The lower end of said stop d^6 is formed with a shoulder d^8 , and the lower end of the stop d^5 is formed with a shoulder, so that in their normal positions the lower ends of the stops fit closely, 15 as shown in Fig. 1. The lower end of the stop d^6 when the stops are in their normal positions extends beyond the arm d , as shown by the dotted line in Fig. 1. There is fastened on the operating-shaft 1 a projecting arm d^{10} , with a contacting wheel d^{11} pivoted at the outer end of same. The operation of the devices is as follows: By a movement of the lever b and the shaft 1, to which it is attached, the contacting wheel b^{11} will move upon the arm d , pushing the arm d toward the lever b^{11} . When the upper end of the pivoted stop d^5 strikes the lever b^{11} , the stop 20 will be thrown from its normal position, as shown in Fig. 7, which will release the pivoted stop d^6 , and the wheel d^{11} will continue to move on the inner end of the cam d . When, however, the pinion b^4 is rotated until the projection b^9 strikes the stud b^8 and moves the lever b^{11} , so that it is moved out of the path of the pivoted stop d^5 , the stops will upon 25 the further movement of the shaft 1 remain in their normal positions, as shown in Fig. 1, the inner edge of the stop d^6 extending beyond the arm d , and the wheel d^{11} will thereupon move the arm d , caused by the stops remaining in their normal positions, to cause the rack-bar a^4 to make an additional movement upwardly equal to the movement of one 30 tooth of the pinion b^4 , which will cause the corresponding counter-wheel to rotate one additional tooth. A pin b^{17} , projecting from the arm a^8 , which connects the rack a^4 with the arm a^6 when the lever b^{11} is in its normal 35 position, will strike the shoulder b^{16} in its upward course, and thereby limit the movement of the rack a^4 ; but when the lever b^{11} is moved by the lever b^7 the shoulder b^{16} will be thrown out of the path of the pin b^{17} . A pin d^9 (shown in Fig. 3) is attached to 40 the sliding bar c^8 , as shown in Fig. 9. In the normal position of the sliding bar c^8 the upper end of the pin d^9 will strike the arm b^{18} of the pivoted latch and move said latch from the shoulder b^{16} , a spring b^{14} being adapted to 45 press the lever b^7 back to its normal position with the movement of the latch after said latch has released the lever b^{11} . Said sliding bar c^8 is operated by means of the lever e and 50 connections, as fully described in my said Patent No. 642,713. As shown in Fig. 2, there is one set of transferring devices opposite the

bank of ten-cent keys and one opposite the bank of dollar-keys. It will thus be seen that upon each revolution of the pinion b^4 70 the arm b^{11} will be moved out of the path of the pivoted stop d^5 , so that upon the complete movement of the shaft 1 the arm d will cause the rack a^4 to make an additional movement equal to the movement of one tooth of the 75 counting-wheel connected to said rack, so that each complete revolution of the counting-wheel for the bank of cents-keys will be transferred to the counting-wheel of the dollar-keys. Upon the movement of the sliding plate c^8 from its normal position by the operation of said lever e and its connections the pin d^9 will move away from the arm b^{18} of the latch b^{12} , and when the lever b^{11} is moved from its normal position the latch b^{12} will then drop 80 over the shoulder b^{16} and hold the lever b^{11} out of the path of the pivoted pawl d^5 , and upon the return of the sliding plate c^8 to its normal position the pin d^9 will lift the latch and permit the lever b^{11} to return to its normal position. It will thus be seen that I have provided a very simple and effective means of transferring from one counting-wheel to the wheel of the next higher denomination. 85

In Figs. 5 and 6 I have shown an improved 90 device for use in machines employing separate banks of cash-keys for each denomination—cents, dimes, and dollars—and by my improved device separate banks of cash-keys may be connected, so that keys in separate 95 banks may be operated together in a single operation, and thus dispense with separate operations for each bank of keys. For this purpose I have shown a plate f with a hooked arm f' extending from one side, which plate 100 is adapted to be pivoted on the key-shaft 2, so that the hooked arm f' will rest upon any desired key in the bank of keys in the next denomination. In the device shown I have the arm f' with its hook end resting upon the 105 five-cent key and have thus connected the dime bank of keys with the five-cent key of the cents bank of keys. The plate f has flanges f^2 and f^3 , arranged so that one of said flanges will rest near the upper tier of keys 110 and the other to rest near the lower tier, extending along the entire bank of dime-keys, so that the operator when moving any one of the dime-keys may at the same time move the plate f , so as to cause the five-cent key, 115 to which the arm f' is connected, also to be depressed and at the same time operate the two keys together in one single operation.

Having thus described my invention, I claim—

1. The combination of registering devices, operating devices therefor, a movable stop-lever normally limiting the movement of the operating devices and means for moving said stop-lever in order that the register-operating devices may be positively moved a predetermined additional distance, by the same means the initial movement was given; for the purpose of making the transfer.

2. The combination of registering devices, a movable rack, operating devices therefor, a movable stop-lever normally in the path of and for limiting the movement of said operating devices, connections from said rack to said movable stop-lever to move the same in order that the register-operating devices, may be positively moved a predetermined additional distance, by the same means the initial movement was given, for the purpose of transferring from one denomination to that of the next higher.

3. In a cash-register, the combination of counting-wheels for different denominations, operating devices therefor, movable stop-levers normally in the path of said operating devices for each denomination, excepting the lowest, and adapted to limit the movement of the counting-wheels of each of said denominations, means for moving any one of said stop-levers thereby permitting by the same means the initial movement was given, a predetermined additional positive movement of the counting-wheels of the next higher denomination equal to the movement of one tooth of said counting-wheels for the purpose of transferring from one denomination to that of the next higher.

4. The combination of registering devices, operating devices therefor, a movable stop-lever and a movable stop, said stop-lever and stop being in the path of the operating devices, the former normally acting to throw the latter out of said path to limit the movement of the operating devices and means for moving said movable stop-lever so as to allow said movable stop to remain in its normal position thereby permitting an additional positive movement of the register-operating devices by the same means the initial movement was given, for the purpose of making the transfer.

5. The combination of registering devices, operating devices therefor, a movable arm, movable interengaging stops on said arm, a movable stop-lever normally acting on said stops to limit the movement of the operating devices and means for moving said movable stop-lever so that it will not act on said stops, thereby permitting a predetermined additional positive movement of the register-operating devices by the same means that the initial movement was given, for the purpose of transferring from one denomination to that of the next higher.

55 6. The combination of registering devices, a movable rack, a pinion with a sleeve thereon, a laterally-movable pinion to engage said rack and pinion, operating devices for said rack and pinions, a movable stop-lever normally in the path of the operating devices to limit the movement of same, a pin on the sleeve of said first-named pinion; a pivoted lever with a stud in the path of said pin, a lever pivotally connecting said last-named lever with said movable stop-lever to move and a latch to hold said movable stop-lever from the path of the operating devices, there-

by permitting an additional positive movement of said rack and register-operating devices by the same means the initial movement was given, for the purpose of transferring from one denomination to that of the next higher.

7. The combination of registering devices, a straight movable rack to engage said registering devices, a lever pivoted to said rack, operating devices therefor, a pin in said lever, a movable stop-lever normally in the path of said pin to limit the movement of the operating devices, connections from said rack to said movable stop-lever to move said movable stop-lever from the path of said pin, thereby permitting an additional positive movement of said rack and register-operating devices by the same means that the initial movement was given, for the purpose of transferring from one denomination to another.

8. The combination of a movable rack, a laterally-movable pinion to engage said rack, counting-wheels operated by said rack and pinion, a lever pivoted to said rack, a pin in said lever, a movable stop-lever normally in the path of said pin, connections from said pinion to said movable stop-lever to move said movable stop-lever from the path of said pin, thereby permitting, by the same means that the initial movement was given, an additional movement of said rack equal to the movement of one tooth of the counting-wheel for the purpose of transferring from the counting-wheel of one denomination to that of the next higher.

9. The combination with a laterally-movable pinion, registering devices geared to the pinion, a straight movable rack to engage said pinion, a lever pivoted to said rack, a pin on said lever, a movable stop-lever normally in the path of said pin, connections from said pinion to said movable stop-lever to move and a latch to hold the same from the path of said pin, to permit a predetermined additional positive movement of said register-operating devices, by the same means that the initial movement was given, for the purpose of making the transfer.

10. In a cash-register, the combination of counting-wheels for different denominations, operating devices therefor, movable stop-levers and movable stops in the path of the operating devices for each denomination, excepting the lowest, the stop-levers normally acting to throw the stops out of said path to limit the movement of the counting-wheels of each of said denominations and means for moving any one of said movable stop-levers so as to allow the movable stop in the same denomination to remain in its normal position thereby permitting, by the same means the initial movement was given, an additional movement of the counting-wheel of the next higher denomination equal to the movement of one tooth of said counting-wheel, for the purpose of transferring from one denomination to that of the next higher.

11. The combination of registering devices, an operating-shaft, an arm attached to said shaft, a contacting wheel pivoted in the outer end of said arm, an auxiliary shaft, an arm attached to said auxiliary shaft, having a face thereon to contact with said contacting wheel, a movable stop pivoted on said last-named arm having a face normally extending beyond the face on said arm, an intermediate movable stop pivoted on said last-named arm normally engaging said other movable stop, a straight movable rack, a lever pivoted to said rack with connections to said operating-shaft, a pin in said lever, a movable stop-lever normally in the path of said pin and said intermediate stop acting to withdraw the face of said first-named stop from contacting with said contacting wheel and to limit the movement of the operating devices, counting-

wheels, a laterally-movable pinion to engage 20 said rack and counting-wheels, connections from said pinion to said movable stop-lever to move said movable stop-lever from its normal position, thereby permitting said first-named movable stop to remain in its normal 25 position and its face to extend beyond the face on said last-named arm, so that said contacting wheel will contact with the face of said stop to give an additional movement to the register-operating devices for the purpose 30 of transferring from one denomination to that of the next higher.

In testimony whereof I have hereunto set my hand this 25th day of March, A. D. 1899.

JOHN PFEIFER.
